UNITED STATES PATENT OFFICE.

FREDERICK P. DODGE, OF NEW YORK, N. Y.

DESIGN FOR A STAGE-SETTING.

SPECIFICATION forming part of Design No. 20,930, dated July 14, 1891.

Application filed June 2, 1891. Serial No. 394,872. Term of patent 7 years.

To all whom it may concern:

Be it known that I, FREDERICK PAULDING DODGE, a citizen of the United States, residing at New York city, in the county and State of New York, have invented and produced a new and original Design for Stage-Settings, of which the following is a specification, reference being had to the accompanying drawing, forming part thereof, in which the figure represents the scenic design in front elevation.

The intention of the design represented and to be hereinafter described is to simulate in novel grouping a water-front thoroughfare, shipping and structures incident to such a street, a mutilated sewer, the breaks therein disclosing water, and an entrance to the sewer in the street.

At one side of the representation of a street 20 A, at the water side, a series of figures B, simulating vessels, are grouped, and figures C,

representing dwellings and warehouses, appear indiscriminately arranged facing the street. Circular, rectangular, and irregular figures are represented upon the street simulating articles of merchandise and traffic, and in the foreground of the design a cylindrical figure D is located, approximating in outline a typical sewer. Panel figures E are arranged upon the sewer figure, and wave-lines F appear upon the panels, arranged to simulate running water. A figure G, simulating a circle in outline, is located upon the street figure, presenting the appearance of an opening in the street. 25 30

I claim—

A design for a stage-setting, substantially as shown and described.

FREDERICK P. DODGE.
